UNITED STATES PATENT OFFICE.

JOHN ROBERT BROWN, OF VANCOUVER, BRITISH COLUMBIA, CANADA, ASSIGNEE OF
ONE-HALF TO ROBERT JARDINE, OF NEW WESTMINSTER, CANADA.

OIL-BURNING SYSTEM.

1,120,441.

Specification of Letters Patent.

Patented Dec. 8, 1914.

Application filed July 25, 1914. Serial No. 853,229.

To all whom it may concern:

Be it known that I, JOHN ROBERT BROWN, a subject of the King of Great Britain, and a resident of the city of Vancouver, in the Province of British Columbia, Canada, have invented certain new and useful Improvements in Oil-Burning Systems, of which the following is a specification.

My invention relates to improvements in oil burning systems, and the object of my invention is to devise an oil burning system the effective operation of which can be started on a moment's notice, and in which the necessity of raising steam by preliminary heating with a wood or coal fire is entirely eliminated.

A further object is to devise an oil burning system adapted to utilize either steam or compressed air, with equal facility and at the will of the operator, for the atomizing of the oil, thereby making the system interchangeable and adaptable to varying standards of oil.

A still further object is to devise an oil burning system the construction of which is such that it can be applied to any boiler without making any structural alterations to the same, and which is simple and easily connected to, or disconnected from, the boiler, so that it is only a matter of a few minutes to convert the boiler from an oil burner to a coal or wood burner, should a contingency arise necessitating such change.

I attain the objects of my invention by the means illustrated in the accompanying drawings, in which—

Figure 1 is a side elevation of my oil burning system, the boiler being shown in section. Fig. 2 is a view of the front end of the boiler. Fig. 3 is a side elevation of the burner, in section.

Similar figures of reference indicate similar parts throughout the several views.

1 represents a portion of a typical locomotive boiler. 2 is the firebox thereof.

3 are the grate bars.

4 are removable fire-bricks covering the grate bars 3.

5 is the ashpit.

6 are draft openings through the firebrick covering 4, made by removing one or two bricks at each end of the firebox as shown in Fig. 1, to allow for the passage of air from the ashpit into the firebox.

7 is a bridge of firebrick.

8 is the furnace door.

9 is the ashpit door.

10 is a pipe coil carried by, and secured on the inner side of, the furnace door 8 so as to extend into the furnace when the door 60 is closed, as shown in Fig. 1. The ends of the coil are carried through the door 8 and are provided with the unions 11 and 12 respectively.

13 is a burner of a kind similar to that 65 shown in Fig. 3, having a pair of nozzles 14 and 15 extending into its atomizing chamber 16, which nozzles are positioned one directly above the other, the upper nozzle 14 being for oil and the lower one 15 for steam 70 or air. The outer ends of these nozzles are adapted for the connection of pipes thereto.

17 is the main oil storage tank, from which the oil is taken when the boiler is under full steam.

18 is a supplementary oil storage tank, suitably supported on the top of the main tank, and which tank always carries oil, up to a certain level, to be used when starting up, as hereinafter described more fully.

19 is a compressed air storage tank suitably supported on top of the main oil tank 17 and preferably in proximity to the supplementary tank 18.

20 is a ventilator pipe, and 21 a filling 85 pipe, for the main tank 17.

22 is a ventilator pipe from the tank 18 leading into the main ventilator pipe 20.

23 is the manhole door giving access into the main tank.

24 is a drain from the main tank.

25 is a steam driven pump, having an oil cylinder 26 and an air compression cylinder 27, by means of which the oil is drawn from the tank 17 and delivered to the burner 13 95 and also the air for atomizing delivered to the tank 19.

28 is the steam pipe for the pump 25.

29 is the exhaust pipe thereof.

30 is the air discharge pipe from the cylinder 27 to the air storage tank 19.

31 is the air supply pipe from the air tank 19 to the burner 13, being connected to the lower nozzle 15 by means of the T connection 32, nipple 33, and elbow 34, and adapted for disconnection therefrom by means of the union 35.

36 is a pipe connection between the lower outer end of the coil 10 and the T connection 32 by means of which steam may be 110

supplied to the nozzle 15, and which pipe may be disconnected from the coil by means of the union 11.

37 is a steam pipe connection from the steam space of the boiler 1 to the upper outer end of the coil 10, to which it is detachably connected by means of the union 12.

38 is the oil suction pipe from the main tank 17 to the oil cylinder 26, which pipe is provided with a shut-off cock 39.

40 is an internal oil suction pipe forming a continuation of pipe 38, its inner end being provided with an elbow 41 and extending into a perforated screen 42, which screen is provided to prevent dirt and other matter getting into the pipe 40. The elbow 41 is provided on the end of pipe 40 so that the oil inlet of the pipe will be above the level of any water that may be in the oil and which will form a layer on the bottom of the tank.

43 is a light chain secured to the screen 42 and which chain is led to, and secured near, the manhole of the tank so that the screen may be conveniently withdrawn for cleaning.

44 is the main oil discharge pipe from the cylinder 26 to the burner 13, which pipe is connected to the upper nozzle 14 by means of the elbow 45 and which may be disconnected therefrom by means of the union 46.

47 is the oil discharge pipe from the supplementary tank 18 to the burner, this pipe being connected to the main pipe 44 by means of a suitable T connection 48.

49 is an overflow pipe from the main pipe 44, which pipe is provided for the purpose of conveying surplus oil, not used by the burner, back to the storage tank 18.

50 is an overflow pipe from the tank 18 to the tank 17, provided to insure that the oil will not rise above a certain level in tank 18.

51 is a gage glass for tank 18.

52 is a safety valve for the compressed air tank 19.

53 is a pressure gage for tank 19.

54 is a stop valve on pipe 47. 55 is a stop valve on pipe 49. 56 and 57 are stop valves on pipe 31. 58 is a stop valve on pipe 30. 59 is a stop valve on pipe 36. 60 is a stop valve on pipe 44. 61 is a stop valve on pipe 37, these stop valves being provided as shown for opening and closing their respective pipes, hereinbefore described, of the system.

Having thus indicated the principal parts of my invention I will now describe the manner in which it operates. When my system is ready for operation the main tank 17 is full of oil, the supplementary oil storage tank 18 contains oil up to its normal level, that is, up to the level of the overflow pipe 50, and the tank 19 contains compressed air at suitable pressure. The stop valves on all the pipes will be then closed. Now, to start

up, the stop valves 60, 54, 55, 56 and 57 on pipes 44, 47, 49, and 31, respectively, are opened, allowing the oil to flow from the storage tank 18 to the burner nozzle 14 into the atomizing chamber 16 where it is atomized by the compressed air stored in tank 19, fed under pressure through pipe 31 to the nozzle 15, and being ignited continues burning until sufficient steam has been generated to start the pump 25. It will be understood, of course, that the capacity of the oil and air storage tanks, 18 and 19 respectively, is sufficient to keep the burner going until steam has been raised in the boiler for starting the pump 25 to draw from the main tank 17. Sufficient steam having been generated, the stop valves 54 and 57 on pipes 47 and 31 respectively are closed and the stop valves 61, 59, and 58 on pipes 37, 36, and 30 are opened, also the shut-off cock 39 is opened. The pump 25 is then started and drawing the oil from the main tank 17 delivers it to the burner through pipe 44 to pass out through the nozzle 14 into the chamber 16 where it is atomized by the steam passing through the nozzle 15 from the pipe 37, superheating coil 10, and pipe 36. The atomized mixture, emerging at the point of the burner within the furnace, continues to burn as long as the supply pipes are kept open. The stop valve 58 on pipe 30 being open, the pressure on this tank is kept constant by the operation of pump 25 so as to be ready for use when required. Should it be found, during operation, that the oil, on account of low standard, is not atomizing well with steam, and as under this condition it is known to atomize better with compressed air, the stop valve 59 on pipe 36 is shut, at the same time opening the stop valve 57 on pipe 31, thereby admitting air to nozzle 15 instead of steam, the change being accomplished in a few seconds without cessation of the firing. In order to keep the oil in the supplementary tank 18 at its normal level so that it is always available for starting up purposes, the pump 25 delivers four times as much oil to the burner as it requires for firing purposes, the excess oil passing, under pressure, through the overflow pipe 49 back into the tank 18. Should circumstances arise necessitating the discarding temporarily of the oil burning system, the boiler may be immediately adapted for firing with wood or coal by simply shutting off the stop valves of the oil burning system, disconnecting the unions 11 and 12 and swinging pipes 37 and 36 clear of the outer ends of the coil 10. This allows the furnace door 8 to be opened and closed in the usual manner. After the fire-bricks have been removed, the boiler is ready for firing with wood or coal. It may be mentioned that natural draft when using oil is obtained by means of the openings 6, 130

and that the natural draft prevents the burning out of the coil 10, since there is always a current of air passing around the coil.

5 It will be seen, therefore, that I have devised an oil burning system which is self-starting, is adapted to utilize either steam or air, with equal facility, for the atomizing of the oil, and which can be applied to 10 any boiler without necessitating structural alteration to the same. It will also be seen that my system can be easily and quickly disconnected from the boiler to enable the boiler to be fired with wood or coal again 15 if necessary, and thus repairs may be executed to the oil burning installation without putting the boiler out of commission.

What I claim as my invention is:

In an oil burning system, the combination 20 with a boiler having the usual furnace, furnace door, and grate bars, a removable heat insulating floor covering the said grate bars and having a plurality of draft openings therethrough, and a burner having a steam 25 or air nozzle and an oil nozzle extending into the furnace through the furnace front and supported thereon below the said furnace door, of a steam coil on the inner side of said door having its ends extending outwardly therethrough and respectively in detachable connection with the steam space of 30 the boiler and the steam or air nozzle of the

burner, said coil being adapted to swing with the door when opening or closing same, a main oil tank, a supplementary oil tank, 35 a compressed air tank, a suitably operated pump, a suitably operated air compressor, a suction pipe connection between the pump and the main oil tank, a discharge pipe connection between the pump and the oil nozzle, a pipe connection between the supplementary oil tank and the pump discharge pipe, a tank overflow pipe connection from the supplementary oil tank to the main tank, a burner overflow pipe connection from the 40 pump discharge pipe to the supplementary oil tank, an air discharge pipe connection from the air compressor to the compressed air tank, a pipe connection from the said air tank to the steam or air nozzle, and valves 45 for opening and closing all the said pipe connections, said valves being disposed so as to provide for the admission of steam or air to the steam or air nozzle interchangeably from the steam space of the boiler or the compressed air tank and of oil to the oil nozzle interchangeably from the main oil tank or the supplementary oil tank. 50
